CORPORATION OF NEW YORK.

RADIO APPARATUS.

Application filed October 14, 1921. Serial No. 507,663.

This invention relates to radio apparatus for use in radio communication for reception and transmission. The invention in particular relates to combined open and closed aerials of the type described in my Patent 876,996, and in my pending applications, Serial No. 368,903 filed March 26, 1920, and Serial No. 379,405 filed May 6, 1920, the present application constituting a continuation in part of application No. 368,903. The apparatus disclosed in the patent and applications above-mentioned relates to aerials having different directional properties in any given plane such as a closed loop aerial combined with an open vertical aerial in which the currents set up in the aerials are combined for unilateral reception, as in direction finders and radio compasses and for the elimination of static as in transatlantic communication, or both.

Heretofore, apparatus has been designed for reception in a horizontal plane, and the reception characteristics of aerials have been studied principally, if not exclusively, in that plane.

An object of the present invention is to provide aerials having three-dimensional characteristics designed to receive useful signals directionally in all planes, i. e., a three-dimensional direction finder or radio compass, and to eliminate static coming from any point in altitude or azimuth, i. e., from any direction in space.

On November 5, 1919, I presented a paper before the Institute of Radio Engineers on "Static elimination by directional reception", in which paper I discussed the results of my investigations on static and the reception characteristics of aerials not only in the horizontal plane, but also in three-dimensions. The paper with figures was published in the "Proceedings of the Institute of Radio Engineers," for October, 1920, but I will briefly outline and discuss the reception characteristics of such aerials in so far as they may serve to elucidate and explain the present invention.

In the accompanying drawings,

Figures 1 to 5 inclusive are diagrams or reception curves illustrating the directional properties of open and closed aerials and their combinations;

Fig. 6 is an elevation illustrating one em-

bodiment of the invention more especially adapted for direction finding;

Fig. 7 is a diagrammatic view showing the wiring of the construction of Fig. 6;

Fig. 8 is a diagrammatic view of another embodiment of the invention more especially adapted for elimination of static than for direction finding.

In Fig. 1 is shown the now-familiar reception curve of a vertical loop or closed aerial in a horizontal plane, consisting of a cosine curve drawn in polar co-ordinates. This is an ideal curve; actually a coil aerial gives a more or less distorted figure-of-eight, sometimes tending to an hour-glass shape, and usually more or less unsymmetrical. In a vertical plane, including the plane of the loop itself, reception for a closed loop is symmetrical, and the reception curve in this plane is a circle, as shown in Fig. 2. If the loop is near the ground, it does not receive from points below the horizon; and the reception curve for a loop in a vertical plane including the loop is a semicircle as illustrated in full lines. However, if the loop is elevated sufficiently above the surface of the ground, such reception curve in a vertical plane including the plane of the loop will be a circle as shown in Fig. 2, partly in full and partly in broken lines. This would be true if the loop is placed aloft as on an aircraft. Finally, the complete three-dimensional reception surface of the loop is a torus, not illustrated, but see article above referred to, Fig. 12; that is, a doughnut-shaped figure with the contracted central portion tangent to a line drawn normally thru the center of the loop. The significance of the reception curves of Figs. 1 and 2 is obvious; that is, the closed loop can receive more or less from all points in space excepting only along a line passing normally thru its center. The reception of a loop is also dependent upon the plane of polarization of the waves; that is, the orientation of the source or transmitter, and this is fully set forth in Fig. 19 of the article, and the description thereof. The torus-shaped figure or surface of reception is, as explained in the article, true for sources of all possible orientation of the source of waves. A further meaning of Figs. 1 and 2 is that maximum reception for a loop is in

55

65

75

80

90

95

100

105

all directions in the plane including the loop; that is, for a loop having its plane in an east and west direction, the zone of maximum reception is a belt across the sky from east to west, reception decreasing to zero on the horizon at points north and south of the loop.

The so-called open antenna, which usually consists of a vertical wire, short as compared with a wave-length, has in the horizontal plane a simple circle reception diagram, that is, it receives equally well from all points on the horizon. Such a diagram would be such as disclosed in Fig. 2, in which the antenna is arranged vertically of the point O, reception being equally in all directions in the horizontal plane as indicated by the circle. In any vertical plane passing thru the antenna, a quite different reception curve results, as reception is a maximum on the horizon, and decreases to zero at the zenith. The complete curve in any vertical plane passing thru the antenna, therefore, would be a figure-of-eight such as disclosed in Fig. 1 and discussed in connection with the loop; that is, when the antenna is near the ground, its reception figure would be so much of the figure-of-eight of Fig. 1 as is above the line A, B, Fig. 1. However, if this antenna were spaced vertically from the earth a sufficient distance, the complete reception curve in a vertical plane would then be a figure-of-eight. In other words, the reception curve of an open antenna in a vertical plane passing thru it is the same as the reception curve of a closed loop in a horizontal plane. Actually, as with the loop or coil aerial, and for similar reasons, this ideal curve for the open antenna usually suffers considerable distortion, partly because actual vertical aerials have an appreciable horizontal length in most cases, and partly because of unsymmetrical or electrically-warped surroundings. The complete three-dimensional reception surface of the open antenna is therefore just like the closed loop reception surface, being a torus, but arranged in planes 90° apart.

In this connection, there has been much discussion as to the direction or directions from which static comes. However, if static come solely from above, the zenith, a symmetrical open antenna would make a perfect static eliminator. Equally, if static came in on the receiving point with the same intensity from all points in altitude and azimuth, it would be difficult to account for the well-known freedom of the loop from static. But if we assume in general that static is at its worst near the horizon rather than the zenith and comes from a point or a small area instead of from all around the horizon, it will be obvious why the loop is a much better static eliminator than the open aerial.

It is now known, as a result of careful

measurements, that static waves come in on the receiving station from the horizon, i. e., with a practically vertical wave front. See L. W. Austin, "The Wave-Front Angle in Radio-Telegraphy", Washington Acad. Sci. 70 J. II, pp. 101-106, March 4, 1921.

As disclosed in my patent above referred to and also in the applications above referred to, it is my practice to couple the open aerial and the closed loop together with the open and closed aerials at approximately the same point in space relative to the transmitted wave-length, (i. e., the open and the loop aerials are either at the same point in space, or are but a very small fraction of a wave-length apart), and to add the currents received in the open and closed aerials in phase in a secondary circuit for affecting a detector or indicator. In such coupled or combined arrangements, if (by providing a loop and open aerial of equivalent dimensions or by coupling adjustment, or by both), the currents from the open antenna are made equal, in their effect upon the secondary, to those from the loop, the result of this addition may be illustrated by a reception curve on the horizontal plane, as shown in Fig. 3. As there illustrated, it will be seen that reception is at a maximum from the direction O—A, is zero from the direction O—B, and has intermediate values from other directions, the complete curve being a cardioid, it being assumed that the distant transmitter is at a point at the right of the figure and that the coupling between the open and closed aerials and secondary is so arranged as to add the currents in the open and closed aerials. Such a circuit, employed as a direction finder, gives the true bearing of the distant station, and does not, as with the simple loop, leave the direction indeterminate by 180°. In a vertical plane including the loop, the reception curve for the coupled loop and open aerial is also a cardioid, as shown in Fig. 4, with a maximum on the horizon at Z, and zero on the horizon at B. Reception from the zenith, that is, along the line O—Z, being limited to the loop, has half the value of reception along the line O—A. In a vertical plane at right angles with the loop and passing thru the vertical antenna, the reception curve of the combined system is a circle, as indicated at Y, Fig. 5.

The complete three-dimensional reception surface is difficult to show in a two-dimensional figure or plan. In Fig. 5, however, I have illustrated the three principal sections of this reception surface. This reception surface section, it will be noted, is made up of a combination of the figures of Figs. 3 and 4 arranged at right angles to each other, plus the surface Y, arranged in a plane at right angles and passing thru line Z—N. This figure is a cardioid of revolution,

which may be more simply described as an apple, with the pit at the origin O. From a consideration of the three-dimensional unilateral reception figure of the combined open 5 and loop aerials, as shown in Fig. 5, it will be seen that static originating at points other than on the horizon in the direction of the distant transmitter will either be weakly received, or, if it happens to originate on 10 the horizon at a point 180° from the transmitter, it will not be received at all.

As fully discussed and disclosed in my co-pending applications above mentioned, the combined open aerial and loop such as 15 shown in my Patent 876,996 is not at present, however, the best arrangement for reducing static. As the effect of static on a receiving circuit is practically pure impact excitation, complex waves will be set up in the two 20 coupled circuits—the loop and the open antenna—with the result that the ideal diagrams illustrated in Figs. 1 to 5 are but roughly approximated. These diagrams are, of course, only true for steady state un- 25 damped wave reception, or for static reception on substantially aperiodic circuits.

The types of combined closed loop and open aerials as disclosed in my applications above mentioned, and in use at Otter Cliffs 30 near Bar Harbor, Maine, for transatlantic communication, are constructed and designed primarily with reference to the horizontal characteristics of reception and not in regard to the three-dimensional reception. 35 Such apparatus, however, was found to be very satisfactory in reception and in the elimination of static, especially when used with a variable resistance inserted in either or both aerials such as disclosed in Fig. 8, 40 this resistance being for the purpose of damping the oscillations caused by static upon the coupled circuits of the receiving apparatus as more fully described in said applications and hereinafter, such resistance being generally of the order of thousands 45 of ohms; for example, 1,000 to 10,000 ohms, its exact value depending upon the circuit characteristics, wave-length, etc.

As a result of my investigations at Otter 50 Cliffs and study of aerials in three dimensions, I have devised the arrangement of open and closed aerials disclosed in Fig. 8 as the most satisfactory, primarily for the elimination of static. Examination of Fig. 55 will show if this figure is turned thru 90° (clockwise), so that the vertical plane Y becomes the horizontal plane, a very favorable reception surface results. No energy such as static would be received from the zenith and a very little from the rest of the hemisphere until the horizon was reached. On the horizon, from static sources having 60 all possible planes of polarization, there would be reception from all directions, but 65 for signals from distant transmitters the

predominant reception would be from the loop which lies with its plane in the plane of the transmitter, so that signal reception would be directional, and so that the circle Y of Fig. 5 would be changed to a figure of 70 eight such as that shown in Fig. 1. In order to turn through 90° the reception surface of a circuit, such as a combined closed loop and open vertical antenna adjacent the earth, and to obtain the advantages of this 75 invention, I found it necessary to shift such vertical antenna thru 90° in the plane of the loop. This results in the construction illustrated diagrammatically in Fig. 8 in which A is a closed loop aerial having in series 80 therewith a tuning condenser C and an adjustable resistance R. Arranged horizontally relatively to the ground and symmetrically with the loop A but insulated therefrom is an open aerial B having inserted 85 centrally thereof an adjustable condenser C' around the terminals of which is a shunt having a coil L' coupled to a coil L² in the closed loop A forming an adjustable coupling M for transferring in phase 90 the energies received in the closed loop and in the open aerial to one or the other, combining them, and constituting means for eliminating static. A secondary circuit S having a coil L² therein is adjustably coupled as indicated at N to coil L³, or, if so desired, to coil L'. The circuit S includes any suitable detecting means and indicator (not illustrated) and may also include any amplifying means. I have found it best to remove 95 the circuit disclosed in Fig. 8, somewhat from the earth's surface, and I have observed that in general, if the lower part of the loop is elevated some five or six meters from the ground, the arrangement will function satisfactorily. 100

In this connection, it must be remembered that, over land at least, wave-fronts are not vertical, but are tilted forward somewhat in the direction of propagation. For example, 110 I have found that at Otter Cliffs the waves arriving from European stations were inclined approximately 15° from the vertical. When a tilted wave-front passes the circuit of Fig. 8, it is equivalent to tilting the horizon of this figure, with all that that implies as to the reception surface. Returning to Fig. 5, it will be seen that if the plane Y, assuming that it is now in a horizontal plane, be rotated slightly, counter clockwise 115 around C—D as an axis, one-half of the reception surface will be more or less submerged (below ground), so that reception 120 will be unilateral. This change of position of the reception surface is secured in the 125 physical embodiment of the invention by swinging the circuit of Fig. 8 thru a slight angle, thereby suppressing practically entirely one side of the reception, making the circuit free from disturbance. 130

In the construction of Fig. 8, the horizontal antenna B is either feebly receptive or non-receptive as to the transmitted signal, the loop B being so positioned, with its plane in line with the distant transmitter, as to receive the signal with maximum intensity. Static waves coming from overhead are received by both collectors A and B and are equalized and opposed by couplings L' L^3 L^2 which are adjustable and reversible. Static impulses originating near the horizon at points at right angles to the antenna B will be received by the open antenna only when their plane of polarization is other than vertical, and I have found that in general all waves arriving from the horizon are vertically polarized, perhaps due to attachment to the earth, and hence are either not received at all by the combination, or at most but feebly. On the other hand, static impulses arising at points near the horizon in the plane of the loop will not affect aerial B, and hence cannot be eliminated without so tilting the apparatus that the horizontal aerial B is affected and the static energizes in the two aerials then equalized and opposed by the couplings. In the latter case, inasmuch as the horizontal aerial B is tilted relative to the ground to cause it to be normal to the tilted transmitted waves, static waves coming from these directions will also strike the open aerial B at an angle and set up oscillations which can be made equal to and opposed with the static oscillations in the loop. In an embodiment of the invention of Fig. 8 as actually constructed and used, the loop A consisted of seven turns of number 16 Brown & Sharp gauge copper wire (1.3 mm. diameter) spaced 10 cm. (4 inches) apart in a solenoidal coil, 30 meters (91.5 feet) long, 7 meters (21.4 feet) high and with the lower conductors of the loop about 4 meters (12.2 feet) above the ground. The open horizontal antenna B consisted of a single wire 50 meters long, with a variable condenser C' inserted at its center. The coils L' and L^3 were 20 millihenrys each, and the resistance R was 1000 ohms. Preliminary tests having indicated that the open antenna B received materially less energy than the loop A, the resistance R was therefore placed in the loop in order to render the currents in the loop and open aerial more nearly equal, thereby requiring less variation and adjustment of the couplings.

The apparatus of Fig. 8 may be mounted, if so desired or convenient, on suitable universal mountings such as disclosed in Fig. 6, which will be more fully described hereinafter, in order that the combined closed loop and open antenna may be located in the most advantageous relation with reference to the transmitter or with reference to the source of static tending to prevent the clear reception of the signal, and if so desired the open aerial B may be mounted to be swung relatively to the loop A. As an alternative or supplement to such adjustment of the aerials as a whole, the couplings M and N are provided, (Fig. 8) which are adjustable and reversible for the purpose of equalizing and concealing the static energies, and for this purpose it is advisable that reversing switches such as disclosed in my above-mentioned co-pending applications be employed.

Referring to Figs. 6 and 7, I have illustrated a form of the invention which is primarily adapted for use as a radio compass or direction finder on airplanes or balloons or for the purpose of determining from any station the location of distant airplanes or other airships when transmitting. Fig. 7 is a diagram of the circuits involved in the mechanical arrangement of Fig. 6. In Fig. 6 I have illustrated a frame 11 of insulating material, having cross-pieces 12 of similar insulating material. On cross-pieces 12 is secured a loop A of wire forming a multturn loop of any suitable or required dimension. As here illustrated, this loop A is so wound that the several turns thereof lie substantially in the same plane and spaced from each other, altho they may be wound in any suitable manner as conditions may require. The ends of the loop A extend at points 13 and 14 into shielding box 15 secured to frame 11 and containing the adjustable elements of the apparatus as disclosed diagrammatically in Fig. 7. Mounted at diametrically opposite points on the frame 11 (Fig. 6) are aligned two metal rods B constituting an open aerial structurally distinct from closed loop A in the sense of being insulated from it. Conductors 16 and 17 electrically connected to the rods B extend into the box 15 at points 18 and 19 within which they are associated with the adjustable devices more fully illustrated in Fig. 7. The loop A has in series with it an adjustable tuning condenser C (Fig. 7) and an inductance L^3 (Fig. 7) within box 15, (Fig. 6), while the open aerial B has a similar inductance L' (Fig. 7) shunted around which is a variable tuning condenser C', all within box 15 (Fig. 6). The inductances L' and L^3 (Fig. 7) constitute an adjustable and reversible coupling M, whereby the signal currents set up in the open and closed aerials are made equal, and added together and the static currents are made equal and opposed if for any reason this is advisable. I have not illustrated the specific means for adjusting the condensers C and C' and couplings L' and L^3 , as any well-known means may be utilized, such as knobs or handles projecting thru the casing 15 (Fig. 6).

The signal currents in the loop A and open aerial B (Fig. 7) are made equal and added together thru couplings L' and L^3 130

and are then transferred to a secondary circuit S thru an inductance L^2 variably coupled at N to inductance L^3 . The secondary circuit S has associated therewith any suitable detector 20 and usual condenser 21, which parts are located within casing 15, (Fig. 6) and leads 22 therefrom extend outside of the casing and are provided with a filter, diagrammatically illustrated as choke coils 23, these being connected by leads 22 to a telephone receiver 24, Fig. 6. This filter, which for some purposes may consist simply of a pair of choke coils, acts to prevent any disturbing action either from the capacity of the telephone receiver 24 to the operator's body, or from any energy which might be picked up by these leads or by means of any high frequency energy drainage from the system contained in the box 15. The frame 11-12 supporting the aerials A and B is mounted on an axis journaled in a yoke 25, the frame being rotated about its horizontal axis by turning knob 26 which is attached to frame 11-12 and rotatable therewith. A suitable dial 27 attached to frame 11-12 and rotating therewith co-operates with an indicator 28 fixed to yoke 25 for indicating the angular position in degrees of the loop and aerial assembly carried by the frame. The yoke 25 is rotatable about a vertical axis 29, which in turn is rotatably mounted on a base 30. The position of the frame 11 and its aerials in azimuth is observed by means of a dial or graduated circle 31 fixed to the axis 29 and therefore fixed with respect to the base 30. The dial 31 co-operates with an index 32 fixed to the rotatable yoke 25. It will be seen that the aerials are mounted rotatably on both a horizontal and a vertical axis. Both rotations can be imparted to the system by suitably manipulating knob 26.

In the practice of my invention, unless the loop A is of unusually large enclosed area or the sending station is nearby, the secondary circuit S preferably is supplemented by a suitable number of steps of amplification in the manner now well-known in the art. After both the open and closed circuits are tuned together and to the distant transmitter, the couplings M and N are adjusted by successive trial so that when the loop and open aerials are in their position of maximum reception, the energy delivered to the secondary circuit is the same from each. This is best determined by swinging the apparatus into the null reception position where the currents are equal and opposite in phase and should then have no effect upon the secondary circuit.

Inasmuch as the open circuit collector B leads the loop A in phase by 90° , these two circuits are coupled together as well as to the secondary circuit S to preserve this phase relation. The currents are first added

together in phase in the closed circuit A, and then the combined energy is transferred to the secondary S , where it actuates any suitable indicator 24 (Fig. 6). For maximum reception, with additive coupling the apparatus when mounted as in Fig. 6 is so swung that the plane of the loop includes the distant transmitter (except under such circumstances as obtain when the transmitter is in the same vertical plane as both the loop and the open aerials and is horizontally displaced with respect to the axis of knob 26) and at the same time the open antenna B is normal to a line joining the receiving apparatus and transmitter. Similarly, the position of no reception is 180° from that, such position being secured by swinging the loop thru 180° on the open antenna as an axis without changing the position of the open antenna. As is common practice with two-dimensional direction finders employing my loop, the null point preferably is used for determining the bearing of the distant station. The apparatus is swung in altitude and azimuth until a point of zero signal is reached, and this determines the bearing of the distant transmitter in three dimensions, i. e., its altitude and azimuth.

The tuning of the several aerials to the desired wave length may be done substantially as follows. First, cut out the closed loop circuit as by loosening the coupling between it and the open circuit or by directly opening the loop circuit at some point (not illustrated). Then vary the condenser C' (or its equivalent inductance) until the maximum signal is obtained in the open aerial. Then open or otherwise remove from the circuit the open aerial and tune the closed circuit by means of the condenser C until maximum response is obtained. Then restore the open circuit, and the combined system is ready for use. The tuning can be done in the reverse order if so desired. In each case the aerials should be receptively positioned relative to the distant transmitter. Altho I have illustrated inductances L' , L^2 and L^3 as being more satisfactory and easier to manipulate, yet it is to be understood that any suitable means of coupling the open and closed circuits may be employed. The open aerial may be tuned by an inductance if so desired such as the inductance L' .

It is necessary that the currents in the two circuits A and B when at their maximum be equal in their effect upon the secondary S in order to secure a null point on opposition or the maximum signal upon addition of the equal currents. Otherwise, the reception characteristic curves disclosed in Figs. 1 to 5 will not apply. A change in degree of coupling, of course, changes the amount of energy transferred from one circuit to the other (Figs. 6, 7, and 8), and

altho it would be possible to so proportion the dimensions of the open and closed circuits that their reception would be equal, it is much easier to make the adjustment by 5 simple change in coupling. Furthermore, inasmuch as the received current in a loop follows a different law of variation upon change of wave-length from that of an antenna, a given loop and open aerial would 10 be in adjustment only at one wave-length, however carefully they were constructionally proportioned. When the combined open and closed aerials of the present invention are so located as to give a null 15 point or no response with reference to a distant transmitter, this means that the current in the loop and open aerial are equal and opposite and they cancel out in respect to the secondary and no signal results. A 20 single simple loop has two null points in a horizontal plane, Fig. 1, which are, of course, the two lines normal to the loop; but when the single loop is combined with an open antenna, there results but one null 25 point, and this is 90° from the null points of the loop alone, Fig. 3.

The function of the resistance R in series with the loop, Fig. 8, if used, is to prevent the impact excitation of static or other disturbances from setting up complex or 30 coupling waves in the system as a whole. Such complex oscillations result from the successive transfer and retransfer of energy between coupled circuits of feeble damping 35 and are objectionable in my invention because they tend to destroy or impair the directional reception of the system on which the elimination of disturbances depends. By increasing the damping of the 40 loop aerial, which is most readily done by the insertion of the resistance R as shown in Fig. 8, such transfer and retransfer of energy is prevented and no coupling waves are formed. The preferred place for the 45 insertion of the resistance R is in the aerial whereby the insertion of the resistance tends to make the currents in the two aerials more nearly equal. When the open antenna is horizontal, Fig. 8, it is preferable to 50 insert the resistance in the loop. The resistance R therefore performs two functions: first, the damping of the system to prevent complex wave formation, and second, the reduction of the current in the 55 closed circuit to approximate equality with that in the open circuit.

In using the circuits disclosed in Fig. 8, the operator first opens the antenna circuit, then tunes the closed circuit to the desired 60 distant station by first coupling the loop with the secondary S and noting the signal strength as the capacity C is varied. During this tuning, it is advantageous to reduce the resistance R to zero in order to note the effect 65 of the tuning more readily. When the maxi-

mum response is obtained in the secondary circuit S as evidenced by the response of the telephone, the magnetic loop of circuit A is opened and the open antenna closed. The open antenna circuit is then tuned to the same 70 distant station by varying inductances L' or L^2 until maximum response is obtained in the secondary circuit S . After both open antenna and magnetic loop circuits are tuned, the resistance R is increased from zero until the 75 maximum static elimination is obtained, this resistance R being a non-inductive variable resistance having a range say from zero to some thousands or tens of thousands of ohms. In aerials of the size and dimensions herein specified, this resistance will be, when in use, of the order of some hundreds or thousands of ohms, depending upon the wavelength and constants of the circuits. 80 Then the operator varies the coupling between the inductances L' and L^2 until a further reduction in disturbance is reached, and finally slightly retunes the loop and open antenna circuit. These steps may be 85 performed in any desired order and may be 90 repeated until the best reduction of disturbance is noted. The effect of these various 95 adjustments seems to be to produce in the two aerials currents due to static which are opposite in effect upon the secondary, so that when they are added, their effect is nil. For this purpose, where the aerials are not 100 rotatable, it is preferable that the coupling coils be reversible, so that the static energies can be opposed, reversing switches for this 105 purpose being shown in my co-pending application, Serial No. 379,405, above-mentioned. The signal waves, however, owing to the directional properties of the system, 110 are not in general equal and opposite in their effects upon the secondary but add to produce a useful signal. It is important that the currents due to static disturbances in the two aerials be opposed in their effect upon the secondary, or otherwise they would 115 add to produce a strong disturbance. To ensure this, the operator may reverse one aerial with respect to the other by reversing the coupling coils as by switches illustrated in 120 said application.

The circuit arrangement of Fig. 8 as well as that of Figs. 6 and 7 avoids the undesirable effects of out-of-phase current in the system present when the open aerial is directly connected to and forms a part of the 125 loop, as disclosed in Fig. 3 of my Patent 876,996 above-mentioned. In the present invention, out-of-phase currents are prevented by not connecting the magnetic loop to earth at all, but employing an open antenna which forms no part of the loop, altho it is within the scope of the invention to use any combination of closed loop and open horizontal aerial securing unilateral reception and a null point from overhead.

In the systems illustrated in the accompanying figures, means for bringing into phase both sets of currents in their action on the receiving apparatus consists in employing the coupling between coils L' and L^3 and L^2 , the two tuned circuits being coupled together, energy in the form of oscillating or alternating current of one circuit being transferred to the other by means of such coupling. In the transfer, the phase is changed by 90° , so that in this system the currents flowing in the open circuit normally 90° out of phase with currents flowing in the loop circuit transferred by way of the couplings between coils L' and L^3 to the loop circuit are changed in the phase by 90° and are so made equal in phase with the currents already existing in the loop circuit.

In the use of combined open and closed aerials, primarily for the reception of signals and the elimination of static (Fig. 8) as distinguished from purely direction finding or radio compass purposes, (Figs. 6-7), the aerials when of the larger dimensions are preferably so located that the closed coil is in line with the distant transmitter or transmitters, the static being preferably eliminated by an adjustment or manipulation of the coupling coils as described in my copending application, Serial No. 379,405.

The same and possibly more satisfactory results as to the elimination of static may be obtained by mounting the combined open and closed aerials in the manner disclosed in Fig. 6, but this method is adapted for the smaller-sized aerials such as direction finders or radio compasses. The action and principles involved, however, are the same, and by the addition of the resistance R disclosed in Fig. 8 to the circuits of Fig. 7, the device in Fig. 6 will serve as a very useful eliminator of static whenever necessary. When the construction of Fig. 6 is rotated to bring the open aerial into the horizontal and directed toward the distant transmitter, we have the positions of aerials as shown in Fig. 8. The construction shown in Fig. 8 is therefore preferably fixed on account of the over-all size of the aerials, altho even in the lack of a universal mounting as in Fig. 6 the open aerial B of Fig. 8 may be and preferably is tiltable about a horizontal axis in order to submerge its characteristic curve, Fig. 5, as described above so as to further decrease the effects of static.

The aerials above-described are adapted for use not only in receiving but also in transmitting. In receiving, any well-known receiving apparatus or detector, such as crystal detector or audion, may be used, either with or without association therewith of steps of amplification as is well known in the art, the detector and amplifier equipment used depending upon the dimensions of the receiving aerials and the power and dis-

tance of the transmitting station. When used for transmitting, a suitable source of high frequency current replaces the detector circuit.

It is believed that while static disturbances may arrive at a receiving station from various directions in altitude and azimuth, the greater part of the disturbance comes in on the receiving station from the horizon. According to my observation on the North Atlantic coast, the less bothersome form of static appears to come indeterminately from many points in the hemisphere, altho with a preponderance toward the horizon. The more bothersome forms of static, however, are localized and on the North Atlantic coast come mainly from the southwest, so that by adjustment of the apparatus as described, their effects are greatly diminished.

In the use of a universally-mounted aerial as shown in Fig. 6 as a static eliminator, it may be preferable under some circumstances to so locate the loop and open antenna with reference to the source of static that it is in large measure eliminated. This can be determined by so positioning the loop and open aerial, by moving them on their axes, that the static effects are the least noticeable. Thereafter the static can be totally eliminated by equalizing and opposing the static currents in the two aerials by manipulation and adjustment of coupling coils, leaving a sufficient amount of useful signal energy to be audible. Where the apparatus of Fig. 6 is used as a direction finder, the loop and open aerial are rotated around their vertical axis, or horizontal axis, or both, until no signal is heard, that is, when (Fig. 5) the pit or null point of the cardioid reception surface is pointing at the distant transmitter. When this occurs, the loop is in line with the transmitter as previously indicated, while the open aerial is at right angles to the line of propagation of the electromagnetic waves, whereby the direction of the transmitter can be easily determined wherever it is, either on land or on an airship, or elsewhere.

In order to obtain neutralization and opposition of static, it is necessary that the static currents received by the collectors A and B when combined must have substantially the same amplitude, frequency and decrement or damping. In other words, neutralization only takes place when the energies are at every instant during the wave train produced by static equal and opposite. This result is secured by the present invention.

It is to be understood that the invention is not limited to the embodiments and features specifically shown and described herein, but that such embodiments and features are subject to changes and modifications without any departure from the spirit of the invention.

I claim:—

1. Three-dimensional directive radio apparatus comprising aerials having different directional properties but arranged in the same plane; means for pivoting said aerials permitting their simultaneous movement to any angular position in space while maintaining them in their said common plane; and a local circuit coupled to said aerial system.

10 2. Three-dimensional directive radio receiving apparatus comprising open and closed aerials, means for adding and detecting currents therein; and a universal mounting for both said aerials whereby they may 15 be simultaneously shifted into any desired angular position in space while maintaining their relation to one another.

3. Three-dimensional directive radio apparatus which comprises an aerial system 20 including two aerials of different directional characteristics, namely a closed loop aerial and an open antenna aerial, said aerials being disposed in substantially the same plane and symmetrically with respect to one another and inductively coupled together, the coupling being adjustable and reversible to permit equalization and cancellation of static energies, the open aerial forming no part of the closed aerial, the closed aerial being insulated from earth, and the open aerial being arranged generally parallel to the earth; and means for tilting the open aerial about a horizontal axis to submerge its characteristic curve and decrease the effects of 30 static.

4. Directional radio apparatus comprising a base, a yoke pivoted to said base on a vertical axis, a frame pivoted to said yoke on an axis at right angles to the first-mentioned 40 axis, open and closed aerials having variable couplings and tuning devices supported by said frame, and a box mounted on said frame and containing said variable couplings and tuning devices.

45 5. Three-dimensional directive radio apparatus which comprises an aerial system including two aerials of different directional characteristics, namely a closed loop aerial and an open antenna aerial, said aerials being disposed in substantially the same plane and symmetrically with respect to one another, and being inductively coupled together but each insulated from earth and from one another, the open aerial forming no part 55 of the closed aerial and being disposed generally parallel to the earth; and means for moving the open aerial.

60 6. Three-dimensional directive radio receiving apparatus comprising a loop aerial, an open aerial, a secondary circuit, coupling means for said aerials and circuit, and a universally movable frame on which said aerials, circuit and coupling means are mounted.

65 7. Three-dimensional directive radio ap-

paratus comprising a frame, a loop aerial and open aerial mounted on said frame, tuning devices for said aerials mounted on the frame, a secondary circuit mounted on the frame, couplings between said aerials and circuit and mounted on the frame, and means for supporting said frame for substantially universal movement.

8. Three-dimensional directive radio apparatus comprising a frame having a closed 75 loop aerial mounted thereon, an open aerial also mounted on said frame and insulated from said loop, means for combining the currents set up in said aerials and detecting the same, and a substantially universally 80 movable mounting for said aerials.

9. Three-dimensional directive radio apparatus comprising open and closed aerials mounted for movement substantially universally, means for combining the currents 85 set up in said aerials and detecting the same, and means for moving said aerials simultaneously and substantially universally.

10. Three-dimensional directive radio apparatus comprising a frame having a closed 90 loop aerial mounted thereon, an open aerial comprising a pair of rods mounted in alignment on said frame, means for coupling said aerials together and tuning the same and mounted centrally on said frame, a secondary 95 circuit coupled to said aerials and mounted on the frame, and a mounting for substantially universally pivoting said frame and aerials.

11. A three-dimensional directive radio 100 system comprising a closed loop aerial, two metal rods mounted substantially diametrically of the loop aerial and arranged symmetrically therewith about a common point and constituting parts of an open aerial; 105 means for coupling such closed and open aerials with one another; means for swinging said aerials simultaneously to any desired angular position in space; a secondary circuit coupled to said system and containing 110 a telephone receiver; and means in the telephone circuit for preventing disturbing action on said aerial system by the telephone leads.

12. A three-dimensional directive radio 115 system comprising a closed loop aerial, an open aerial arranged substantially horizontally relative to ground and symmetrical with the loop aerial about a common point, the two aerials being located at approximately the same point in space relative to the length of the transmitted waves; means for coupling said loop and open aerials; means permitting the simultaneous tilting of said aerials to cause the open aerial to be normal to tilted transmitted waves; said open aerial being insulated from the loop aerial; and an operating circuit coupled to said combination of loop and open aerials.

13. Three-dimensional directive radio ap- 120

paratus comprising open and closed aerials symmetrically disposed with respect to one another about a common point, said open aerial being arranged in a substantially horizontal plane and normal to the transmitted wave-front, a coupling between said aerials, and a secondary circuit associated with said coupling.

14. A three-dimensional directive radio directive system comprising a closed loop aerial; an open aerial normally arranged substantially horizontally relative to the ground and symmetrically with said loop aerial about a common point, said open aerial being coupled to but otherwise insulated from the loop aerial; means for moving said aerials simultaneously to any desired angular position in space; means for equalizing the currents in the loop and open aerials, comprising a resistance of the general order of a thousand ohms connected in the loop aerial; and an operating circuit coupled to said symmetrical combination of loop and open aerials.
15. Three-dimensional directive radio receiving apparatus comprising a closed loop aerial, an open aerial adjacent thereto; means for moving said aerials simultaneously to any desired angular position in space; an adjustable coupling between said aerials for equalizing and opposing the static energies received by the aerials; and a receiving circuit coupled to said aerial system.
16. Directional radio receiving apparatus comprising a closed loop aerial, an open aerial; means for moving said aerials simultaneously to position the open aerial normal to the transmitted wave-front; said open aerial having a lumped capacity intermediate its ends; adjustable coupling means between said aerials for equalizing and opposing the static energies received thereby; and a receiving circuit coupled with said aerial system.
17. A three-dimensional directive radio system comprising a closed loop aerial, an open aerial inductively coupled to but otherwise insulated from said loop aerial; means permitting simultaneous movement of said aerials to any desired angular position in space; and an operating circuit coupled to said coupled aerials.
18. A three-dimensional directive radio system comprising a closed loop aerial; an open aerial; and means for swinging the loop aerial about its diameter, said diameter being at right angles to the open aerial itself, said aerials being symmetrically disposed about a common point and means permitting the simultaneous movement of the open aerial to any desired angular position in space.
19. A three-dimensional directive radio system comprising a closed loop aerial and an open aerial arranged symmetrically about a common point; the loop aerial being
- 5 mounted to be rotatable about its horizontal and vertical axes respectively; and the open aerial being mounted to be rotatable about the horizontal and vertical axes respectively of the loop and simultaneously with said rotation of the loop aerial.
20. A three-dimensional directive radio system comprising a closed loop aerial and an open aerial arranged symmetrically about a common point; the loop aerial being mounted to be swung about an axis substantially at right angles to the open aerial itself; and the open aerial being mounted to be swung bodily and simultaneously with the loop aerial about a diametrical axis of the loop.
21. A three-dimensional directive radio system comprising a closed loop aerial and an open aerial symmetrically arranged together about a common point; and means for simultaneously swinging both the aerials about the horizontal and vertical axes of the loop aerial.
22. A three-dimensional directive radio system comprising a closed loop aerial and an open aerial arranged symmetrically together about a common point; and means for swinging the loop aerial about its horizontal and vertical axes respectively, and for simultaneously moving the open aerial while preserving its relation with the loop aerial.
23. A three-dimensional directive radio system comprising a closed loop aerial and an open aerial arranged together symmetrically about a common point; and means for swinging both aerials simultaneously within a range of 360° to any desired angular position in space.
24. A three-dimensional directive radio system comprising a closed loop aerial; two metal rods mounted substantially diametrically of the loop aerial and symmetrically thereto about a common point, said rods constituting parts of an open aerial; means for coupling the closed and open aerials; and means for swinging both aerials simultaneously to any desired angular position in space.
25. Directional radio apparatus comprising two aerials, one being of the closed condenser-tuned loop type, and another being of the open antenna type, said two aerials being located at approximately the same point in space relative to the length of transmitted waves; the open antenna aerial being arranged horizontally relative to earth and symmetrically relative to the loop aerial; the open antenna aerial also being insulated from the loop aerial but coupled thereto; and an operating circuit coupled with said aerial system.
26. Directional radio apparatus comprising two aerials, one being of the closed condenser-tuned loop type, and another being of

the open antenna type; said two aerials being located at approximately the same point in space relative to the length of transmitted waves; the open antenna aerial being arranged horizontally relative to earth and symmetrically relative to the loop aerial; the loop aerial containing a lumped resistance; the open antenna aerial being insulated from the loop aerial but coupled thereto; and an operating circuit coupled with said aerial system.

27. Radio receiving apparatus comprising two aerials, one being of the closed condenser-tuned loop type, and another being of the open antenna type, said two aerials being located at approximately the same point in space relative to the length of transmitted waves; means for moving the open antenna relative to the earth to cause it to be normal to tilted transmission; the open antenna aerial being insulated from the loop aerial but coupled thereto; and an operating circuit coupled to said aerial system.

28. Radio receiving apparatus comprising two aerials, one being of the closed condenser-tuned loop type, and another being an open antenna, said two aerials being located at approximately the same point in space relative to the length of transmitted waves; means for tilting the open antenna relative to the earth to cause it to be normal to tilted transmission; the open aerial being insulated from the loop but coupled thereto; means permitting rotation of the loop aerial; and an operating circuit coupled with said aerial system.

29. Three-dimensional directive radio receiving apparatus which comprises an aerial system including two aerials of different directional characteristics, namely a closed loop aerial and an open antenna aerial, said aerials being disposed symmetrically with respect to one another and the open aerial being in substantially the same plane with the closed aerial; the two aerials being inductively connected together; the open aerial forming no part of the closed aerial; the closed aerial being insulated from earth; the open aerial being arranged generally par-

allel to the earth; means for tilting the open aerial about a horizontal axis to submerge its characteristic curve and decrease the effects of static; said arrangement securing uni-lateral reception and a null point from overhead; said apparatus including also a third circuit, of reception by the above aerial system; and an inductive coupling between said third circuit and said system and transferring currents in phase between said third circuit and the two aerials; said last named coupling and the coupling between the two aerials, being reversible and adjustable and permitting equalization and cancellation of static energies.

30. Directional radio apparatus comprising two aerials of different directional characteristics coupled together, and means permitting simultaneous movement of both said aerials to desired positions of the aerial system as a whole while preserving their positions relative to one another.

31. Three-dimensional directive radio receiving apparatus comprising two aerials of different directional characteristics coupled together; means permitting simultaneous movement of both aerials to any desired angular position in space while preserving their positions relative to one another; and means for observing reception by said aerial system when the latter is in any such angular position.

32. Directional radio apparatus comprising two aerials of different directional characteristics insulated from one another but coupled together; and means permitting simultaneous movement of both coupled aerials to any desired angular position in space while preserving their positions relative to one another; the coupling between said aerials being adjustable and reversible.

33. Directional radio apparatus comprising two aerials of different directional characteristics mounted in fixed relation to one another and coupled together; and means for simultaneously moving said aerials to any desired angular position in space while preserving their fixed relation to one another.

GREENLEAF WHITTIER PICKARD.
